(57) **CLAIM**

The ornamental design for a polymeric junction box, as shown and described.

DESCRIPTION

FIG. 1 is a perspective view of a first embodiment of a polymeric junction box in accordance with the present design;

FIG. 2 is a front view of the polymeric junction box shown in FIG. 1;

FIG. 3 is a rear view of the polymeric junction box shown in FIG. 1;

FIG. 4 is a plan view of the polymeric junction box shown in FIG. 1;

FIG. 5 is a bottom view of the polymeric junction box shown in FIG. 1;

FIG. 6 is a left side view of the polymeric junction box shown in FIG. 1;

FIG. 7 is a right side view of the polymeric junction box shown in FIG. 1;

FIG. 8 is a perspective view of a second embodiment of a polymeric junction box in accordance with the present design;

FIG. 9 is a front view of the polymeric junction box shown in FIG. 8;

FIG. 10 is a rear view of the polymeric junction box shown in FIG. 8;

FIG. 11 is a plan view of the polymeric junction box shown in FIG. 8;

FIG. 12 is a bottom view of the polymeric junction box shown in FIG. 8;

FIG. 13 is a left side view of the polymeric junction box shown in FIG. 8; and,

FIG. 14 is a right side view of the polymeric junction box shown in FIG. 8.

In the drawings, the broken lines are for the purpose of illustrating environment only and form no part of the claimed design.
